UNITED STATES PATENT OFFICE.

ALVIN M. BENTLEY, OF OWOSSO, MICHIGAN.

EXTENSIBLE WINDOW-SCREEN.

SPECIFICATION forming part of Letters Patent No. 590,448, dated September 21, 1897.

Application filed February 8, 1897. Serial No. 622,398. (No model.)

To all whom it may concern:

Be it known that I, ALVIN M. BENTLEY, a citizen of the United States, residing at Owosso, in the county of Shiawassee and State 5 of Michigan, have invented certain new and useful Improvements in Extensible Window-Screens, of which the following is a specification, reference being had therein to the accompanying drawings.

- 10 The invention consists in the construction of an extensible window-screen, and particularly in the construction of a metallic connecting-bar between the ends of the wooden rails of the three - sided window - frames, 15 whereby a rigid but light connection is made, which permits at the same time of securing wire-cloth thereto and of retaining it at all points close to the surface of the rails, and, further, in the construction of the sliding connection between the frames, all as more fully 20 hereinafter described.

In the drawings, Figure 1 is a perspective view of a portion of my improved extensible screen, showing the sliding rails and their connection. Fig. 2 is a horizontal section therethrough. Fig. 3 is a sectional perspective view illustrating the action of the metallic connecting-bar and its connection to the rail. Fig. 4 is a sectional perspective 25 view showing the construction of the sliding joint between the rails. Fig. 5 is a cross-section through a pair of sliding rails, illustrating the same connection. Fig. 6 is a cross-section through the blank from which the 30 metallic connecting-bar is formed.

Each frame is made of two three-sided wooden frames, each frame comprising the end bar A and the top and bottom rails B. These rails are of the cross-section shown in 35 Figs. 3 and 4, having a groove C in their inner faces, one side thereof being under cut, as shown at D, or forming what I call a "half" or the "single dovetail."

E is a gain formed on the edge of the rail, 45 which leaves a bead F between the groove C and the gain. To form the connection between each pair of these rails, I take a block G of wood and cut out from one side a V-shaped groove, as shown at H in Fig. 5. This 50 leaves two inclined tongues projecting from either side of the middle portion thereof, the thickness of these tongues being equal sub-

stantially to the depth of the grooves in the rails, these blocks being engaged with the grooves in the two rails, half in each groove, 55 and being secured to the ends of the rails, as plainly shown in Fig. 4, forming the sliding connection between the two parts of the screen and also acting as stops to prevent the withdrawal endwise of the rails. 60

I is a wire-cloth. This is connected to the ends by the strips J and is connected to the side rails by being tacked in the gain E thereof, and the opposite end is secured to and by a metallic connecting-bar K, which is 65 formed in the following manner: A piece of metal is doubled to form a blank, as shown at L in Fig. 6. The edge of the wire-cloth is inserted between the two sides of this strip and then the strip is bent to form an angle- 70 bar, as shown in dotted lines in that figure. This bend in the bar serves without other securing means to hold the wire-cloth to the bar. Each of the wooden side rails is provided with a slot or groove O on its inner edge, 75 in which one member or arm a of the angle-bar is forced, this being done, of course, as the form is being made. The other arm b, having the open lips, through which the edge of the wire-cloth projects, is laid flush and flat 80 against the side of the rail in the gain E, holding the edges of the cloth-wire in that gain, so that there is little or no friction between the wire and the side rails in moving the frames one upon the other. This construction makes an exceptionally good, light, 85 strong, and satisfactory screen with a minimum of labor and expense.

What I claim as my invention is—

1. In an extensible window-screen, two 90 three-sided wooden frames slidingly secured together by means of interlocking devices on the parallel bars of the frame, having securing-slots in their inner faces for the cross-bars, a connection between the end of the 95 bars of each of said frames consisting of a metallic bar formed by bending a doubled sheet-metal blank into an angle-bar, the wire screen secured within said bar, and said bar secured in the frames by engaging one member of the angle in slots in the inner faces of the frame-bars, the other member lying along the inside face thereof. 100

2. In an extensible window-screen, having

two three-sided wooden frames slidingly secured together, of connecting-bars to form the fourth side of such frames, made of doubled sheet metal bent into angle shape, 5 the wire-cloth having its edge bent within said bar, the rails of the frames having gains on their inner edges, and securing-slots at an angle thereto, the ends of the angle-bars having one member engaging in the slots, and 10 the other member lying in the gains of the rails for the purpose described.

3. In an extensible window-screen having two three-sided wooden frames slidingly secured together by means of interlocking devices 15 on the parallel bars, of said parallel bars having securing-slots in their inner faces for the inner cross-bars, having a longitudinal groove undercut on one side only, a mar-

ginal gain E and an intermediate bead F between, of blocks having a V-shaped groove 20 cut in one face only, fitting in the groove in each bar, of connecting-bars for the outer end of the wire-cloth extending between the bars, in the shape of angle-bars and formed of doubled sheet metal, with the wire-cloth 25 within, one member of the angle-bar being engaged in a slot in the inner faces of the sliding bars of the frame and the other member thereof lying in the gain in the side bars, substantially as described. 30

In testimony whereof I affix my signature in presence of two witnesses.

ALVIN M. BENTLEY.
